LUMINAIRE BRACKET

Milo Cullen Harsh, South Milwaukee, Wis., assignor to McGraw Electric Company, Milwaukee, Wis., a corporation of Delaware

Application February 26, 1953, Serial No. 23,805

Term of patent 14 years

(Cl. D48—31)

To all whom it may concern:

Be it known, that I, Milo Cullen Harsh, a citizen of the United States, residing at South Milwaukee, in the county of Milwaukee and State of Wisconsin, have invented a new, original, and ornamental Design for Luminaire Brackets, of which the following is a specification, reference being had to the accompanying drawing, forming a part hereof, in which:

Fig. 1 is a side elevation of a luminaire bracket showing my new design;

Fig. 2 is a front elevational view thereof; and

Fig. 3 is a bottom plan view.

The broken lines shown in the drawing are for the purposes of illustration only.

I claim:

The ornamental design for a luminaire bracket, as shown and described.
